UNITED STATES PATENT OFFICE.

JOHN T. RILEY, OF WEST UNION, IOWA.

DEVICE FOR DETERMINING THE AMOUNT OF BUTTER IN MILK.

SPECIFICATION forming part of Letters Patent No. 437,133, dated September 23, 1890.

Application filed February 3, 1890. Serial No. 338,981. (No model.)

To all whom it may concern:

Be it known that I, JOHN T. RILEY, of West Union, in the county of Fayette and State of Iowa, have invented a new and Improved Device for Determining the Amount of Butter in Milk or Cream, of which the following is a full, clear, and exact description.

This invention consists in a novel device, substantially as hereinafter described, and 10 pointed out in the claims, for measuring the butter value of milk or cream—that is, for determining the amount of butter in given quantities of milk or cream of different qualities.

Reference is to be had to the accompanying 15 drawings, forming a part of this specification, in which similar letters of reference indicate corresponding parts in both the figures.

Figure 1 represents in elevation a face view 20 of a device embodying my invention, and Fig. 2 a horizontal section of the same upon the line $x x$ in Fig. 1.

The frame of the device may be of different shapes or be variously constructed, but is here shown as consisting of a lower horizontal 25 piece A and an upright piece B, together with an inclined slideway piece or guide C, rising at an angle of forty-five degrees (more or less) to the piece A, and an upright scale-carrier D, extending upward from or near the base of 30 the inclined slideway piece or guide C, which is stationary, as is also the upright scale-carrier D, and therefore both virtually form an integral portion of the frame that might be a simple board.

35 E is a lever pivoted, as at b, to or near the upper end of the inclined slideway piece or guide C and extending at its free end beyond the scale-carrier D; and F is a perpendicular piece or upright having a shelf d, upon which 40 a tube containing the sample to be measured rests. This upright F, which crosses at its upper end the lever E, is fitted below to slide on or along the inclined slideway piece or guide C, so that it will always preserve its 45 upright position—as, for instance, by a slide e, attached to said upright and fitting a slot f in and along the guide C, or, which would be the same thing, fitted with a box to embrace in a sliding manner the guide C. The lever 50 E is also longitudinally slotted, as at g, and the scale-carrier D and upright F are likewise

slotted in direction of their length, as shown at h and i, and said slotted parts or devices D and F are respectively connected with the slotted lever E by loose slides G and H, capable of moving up and down the slots in the uprights D and F and back and forth in the slot in the lever E. Of course in this instance, too, sliding boxes embracing the uprights D and F and lever E may be substituted 60 for the slides and slots, just as it is the right of every mechanic to place a guiding-surface inside or outside, it only being necessary that the devices or sliding connections G and H are free to move up or down the uprights D 65 and F as well as back and forth along the lever E. The one of these sliding devices G may be termed a "level," and the other one H an "index" for operation in connection with a scale I on the upright D. 70

A spring S serves to hold the lever E up to a horizontal position.

To make a measurement of the butter value of milk or cream, I take a sample of the milk or cream in a glass tube and churn the contents and reduce the butter portion of the sample to oil by any of the well-known systems or means. The oil of course rises to the top of the tube and represents the butter which was in the milk or cream. This tube 75 I place upon the shelf d of the upright F to measure the quantity of butter contained in it, as represented by the oil, which at "100" (indicated on the scale I in the operation of the apparatus) is par, or, in other words, the 80 amount indicated by the unit of measure, that in some localities is one inch deep in a pail or circular measure of twelve inches in diameter, will, by the indication of the oil in the sample at 100 on the scale I, show that the 85 amount of milk or cream in the pail will make a pound of butter, or one and a half pound of butter if the indication on said scale is 150, and half a pound only if the indication on the scale is 50, and so on for each unit of 90 measure contained in the pail or circular vessel; but these indications are arbitrary, as is also the quantity of milk or cream in the pail 95 from which the samples are taken. Now it should be observed that some sample-tubes 100 contain more than others, and with other systems of measuring it is difficult to get the

correct per cent. of the butter value of the milk or cream when this occurs. This difficulty my invention overcomes, as will be evident from the operation of the apparatus.

- 5 To measure a sample, I place the sample-tube bottom down on the horizontal shelf *d* of the upright or sample tube-carrier *F* and slide the latter up or down on the inclined guide *C* until the top of the oil in the tube is
 10 in line with the level *G* when the lever *E* is horizontal. The lever *E* is then depressed until the level *G* is drawn down the upright *F* to the bottom of the oil in the tube, when the index *H* will mark, as it is moved by the
 15 lever *E* down or on the scale *I*, the percentage of oil or butter in the tube. Now, supposing the sample-tube to be only partly or "short" filled, it will be necessary to adjust the upright *F*, carrying the tube, farther up the inclined guide *C*, thus bringing the tube nearer
 20 the pivot *b* of the lever than if the tube were "correctly" or "long" filled, in order that the oil in the tube be brought to its first position—that is, with its top in line with the level *G*
 25 when the lever *E* is up to its horizontal or extreme upward position; and, again, on the other hand, if a still deeper or "longer" filled tube be used it will be necessary to adjust the upright *F* still farther down the inclined guide
 30 *C* to bring the top of the oil in it in line with the level *G* before the latter is moved down. To illustrate this and the necessary depression of the lever *E* to indicate by the index
 35 *H* on the scale *I* a correct measurement in each case, let us suppose the dotted lines 1, 2, and 3 to represent tubes of different length which have been filled up to the point indicated by the letter *m* in each case from milk or cream of like quality. These tubes will
 40 necessarily have to be set up or down the inclined guide *C* by the adjustment of the upright *F* to bring the top of the oil or point *m* in line with the level *G* when the lever *E* is in its raised position. The samples contained in these tubes being greater or lesser
 45 in quantity, the amount of oil representing the butter in them will vary in depth accordingly as the tubes are long or short filled, the nearer the tubes approach the pivot
 50 *b* of the lever *E* the smaller the sample and

the less the oil contained within them, and the farther they are removed from the pivot *b* the larger the sample and the greater the depth of oil in them; but the same percentage of oil will be indicated for them on the scale 55 *I* by lowering the lever *E* to bring the level *G* to the bottom of the oil in either of the tubes, as clearly indicated by the dotted radial line *n* drawn from the pivot *b* as a center. 60

Having thus described my invention, what I claim as new, and desire to secure by Letters Patent, is—

1. In a device for determining the amount of butter in milk or cream, the combination 65 of an inclined guide, a scale-carrier at the lower end of the guide, a lever pivoted at the upper end of the guide, and a sample-tube carrier adapted to slide along the guide, substantially as specified. 70

2. In a device for determining the amount of butter in milk or cream, the combination of an inclined slideway piece or guide, an upright or sample-tube carrier adjustable up or down said inclined guide, a scale-carrier at 75 or near the lower end of said guide, a lever pivoted at or near the upper end of such guide, and sliding connections between the tube-carrier and said lever and between the scale-carrier and the lever movable along the 80 lever and up or down the tube-carrier and scale-carrier, respectively, substantially as specified.

3. In a device for determining the amount of butter in milk or cream, the combination, 85 with the main frame, its stationary inclined guide *C*, and stationary upwardly-projecting scale-carrier *D* at or near the lower end of said guide, of the upright or sample-tube carrier adjustable up or down said inclined 90 guide, the lever pivoted at or near the upper end of such guide, the spring *s*, controlling said lever, and the sliding connections *G H*, moving up or down the tube-carrier and scale-carrier, respectively, and along the lever *E*, 95 essentially as shown and described.

JOHN T. RILEY.
